COMBINATION CARRYING AND DRYING CONTAINER FOR ARTIFICIAL FLY BAIT

James R. Hoffhines and Charles C. Thomas, Detroit, Mich., assignors to Plasti-Print, Incorporated, a corporation of Michigan

Application December 15, 1953, Serial No. 28,080

Term of patent 7 years

(Cl. D58—12)

Fig. 1

Fig. 2

Fig. 3

Fig. 4

Fig. 1 is a front elevational view of a combination carrying and drying container for artificial fly bait embodying my new design;

Fig. 2 is a side elevational view;

Fig. 3 is a rear elevational view; and

Fig. 4 is a top elevational view.

We claim:

The ornamental design for a combination carrying and drying container for artificial fly bait, as shown.
